UNITED STATES PATENT OFFICE.

JULIO H. RAE, OF DAYTON, NEVADA, ASSIGNOR OF ONE-THIRD TO JULIO H. RAE, JR., AND ONE-THIRD TO LOUISA M. RAE, BOTH OF DAYTON, NEVADA.

AMALGAMATING AND CONCENTRATING MACHINE.

Application filed June 30, 1924. Serial No. 723,092.

To all whom it may concern:

Be it known that I, JULIO H. RAE, a citizen of the United States, residing at Dayton, county of Lyon, and State of Nevada, have invented new and useful Improvements in Amalgamating and Concentrating Machines, of which the following is a specification.

This invention relates to an amalgamating and concentrating machine, and particularly to a machine which is adapted for separating fine metal particles from black sand and the like.

In mining districts where placer deposits containing fine or flour gold, platinum and other precious metals are encountered, and particularly where the precious metals are mixed with so called black sands, experience has shown that it is practically impossible to save the fine values. Sluice boxes, concentrating tables, belts, matting and so on have been employed, and numerous forms of riffles and other retaining devices have been used but all to no avail, as the black sand settles and packs to such an extent that the flour or fine values do not have an opportunity to lodge and as such are carried away with the sluice or wash water.

The object of the present invention is to provide a machine which is particularly adapted for handling material of this character, and in which the fine values are caught or retained, first, by amalgamating action and, secondly, by concentration; this being accomplished, first, by passing the material over a bed or surface of quicksilver which is maintained in a constant state of agitation; secondly, by preventing packing of the black sand, thus permitting the values to settle and amalgamate, and, third, by subjecting the black sand to a concentrating action which will separate such values as have escaped amalgamation, or which could not become amalgamated due to the fact that their surfaces were too highly oxidized or perhaps included with other materials such as sulphides, etc.

One form which my invention may assume is exemplified in the following description and illustrated in the accompanying drawings, in which—

Fig. 1 is a central vertical longitudinal section through the amalgamating and concentrating machine.

Fig. 2 is a plan view of the same.

Referring to the drawings in detail, and particularly to Fig. 1, A indicates a sluice box to which the material is delivered after it has been passed through a suitable form of screen, grizzly or other like device which will remove over-sized material, such as heavy gravel, boulders and the like. The black sand and other material separated from the coarser gravel, boulders, etc., together with a sufficient amount of wash water, enter the sluice A and then pass over a series of rollers generally indicated at 2. These rollers are supported on shafts 3 extending crosswise of an enlarged compartment B forming a continuation of the sluice box A. The shafts are suitably journaled in the side walls of the compartment and project therethrough.

The rollers may be constructed of cast-iron, steel or any other suitable material, and the spacing between the rollers is such that only the black sand and fine materials may pass between the same. The coarser material, together with a small proportion of the wash water, passes over the upper surface of the rollers, as the sluice box A and the enlarged compartment B assume an inclined position, and the material is therefore not only advanced by the wash water over the upper surface of the rollers 2, but it is also advanced mechanically due to the fact that the rollers 2 are rotated in unison and in the same direction, as will hereinafter be described.

The upper rollers in reality form a roller form of conveyor or grizzly and the valueless material is thus readily separated from the finer materials and black sands which carry the metal values and it is discharged on an apron 4, which delivers the material to a discharge launder or sluice 5 from where it may be conveyed to any point desired.

Disposed below the rollers 2 is a second series of rollers as indicated at 6. These are also carried by shafts which project through the sides of the chamber B, and these shafts, together with the rollers 6 carried thereby, are also driven in unison and in the same direction as the rollers 2 as will later be described.

The bottom section of the chamber is provided with two or more crosswise disposed partition members such as shown at 7 and 8. These partition members form dams which

retain the mercury generally indicated at 9. The rollers 6 are partially submerged in the separate mercury beds or surfaces maintained by the dams 7 and 8 and, as the rollers 5 are constantly rotating, sufficient agitation is maintained to prevent packing of the black sand and to retain the quicksilver in a live condition, which decidedly promotes amalgamation.

10 The finer sands, together with the black sand and the metal values carried thereby, pass through the spaces formed between the rollers 2 and a sufficient amount of wash water also passes down through these spaces.

15 The water and sand thus delivered to the lower rollers pass between the same on to the mercury beds maintained by the rollers 2 and, as the sand is maintained in constant agitation by the rotation of the rollers, the 20 heavier values will settle to the surface of the quicksilver beds and will here be amalgamated. The lighter sands will be carried forward by the motion of the wash water and also by the continuous rotation of the 25 rollers which carry the sand from one roller to another. The black sand and lighter sands will thus finely discharge over the dams or cross-members 7 and 8 and will thus be deposited on an apron 11. Disposed 30 above this apron is a series of rollers such as indicated at 12. These are mounted and journaled crosswise of the machine in a manner similar to the rollers 2 and 6 and are driven in unison with the same. The 35 cross-strip or dam 13 is placed below these rollers and a dam is thus formed forward of the rollers 12, so that the black sand will have a tendency to accumulate behind the dam. The constant rotation of the rollers 12 maintains the black sand in such a 40 state of agitation that valuable metals which have escaped amalgamation will here have an opportunity to become concentrated or settle behind the dam 13, where the values, 45 together with the major portion of the black sand will discharge through a slot 16. The waste materials and other sand will be constantly advanced by the rollers 12 and by the action of the wash water, and as such 50 will finally discharge over the dam 13 into a discharge launder or sluice 14 from where they may be conveyed to any point desired.

Experience has shown that gold, in many instances, becomes so highly oxidized that 55 it will not amalgamate. Such gold will, therefore, escape the amalgamating action but will be caught in this instance by the concentrating action of the rollers 12. Other values are sometimes included in other 60 metals which are not subject to amalgamation, or they may appear in the form of sulphides or the like and may thus be caught by concentrating action, and it is for this reason that the last set of rollers 12 is employed.

The present machine is not concerned with the retention of heavy values, for instance such as gold nuggets, heavy platinum particles and the like, as these may be caught by ordinary forms of riffles in the upper portion of the sluice box A. The machine is also concerned with the retention of the finer or flour values and actual practice has shown that the machine is exceedingly efficient for this purpose. This is 75 due to the fact that the material to be treated is, first of all, passed through ordinary grizzlies, which remove the coarser gravel, boulders and the like; secondly, because a secondary separating action is resorted to when the material is passed over the roller grizzly formed by the rollers 2; third, that the finer values are permitted to settle between the roller 6, due to the fact that the black sand cannot pack because of 80 the constant agitation induced by the roller 6, and the finer values will thus settle between the rollers and as such will come in contact with the mercury beds. These 85 beds are maintained in a constant state of agitation and the values thus become readily amalgamated. Fourth, any values which may escape amalgamation, due to the fact that they can not amalgamate, due to reasons already stated, are concentrated by the 90 action of the rollers 12 and practically all values are thus either amalgamated or concentrated and retained before the material escapes into the waste launders indicated at 95 5 and 4.

The rollers 2, 6 and 12 may be driven in unison in any suitable manner, for instance, by providing a pair of line shafts which are driven in unison as here illustrated, and by transmitting power from the line shafts by means of bevel gears to the respective shafts. Other driving means may be employed, but as one illustration will suffice, further illustration has not been attempted.

While certain features of the present invention are more or less specifically illustrated, I wish it understood that various changes in form and proportion may be resorted to within the scope of the appended claims. I similarly wish it understood that the materials and finish of the several parts employed may be such as the experience and judgment of the manufacturer may dictate or various uses may demand.

Having thus described my invention, what I claim and desire to secure by Letters Patent is—

1. A device of the character described comprising a sluice box, said sluice having a compartment formed in the bottom thereof for the reception of mercury, a plurality of rollers journaled crosswise of the sluice and partially submerged in the mercury, said rollers being interspaced to permit them to function as separating and conveying

rollers, and means for rotating the rollers.

2. A device of the character described, comprising a sluice box, said sluice having a compartment formed in the bottom thereof for the reception of mercury, a plurality of rollers journaled crosswise of the sluice and partially submerged in the mercury, and a second series of rollers disposed above the first-named rollers, said second series of 10 rollers being interspaced to permit them to function as separating and conveying rollers.

3. A device of the character described, comprising a sluice box, said sluice having a compartment formed in the bottom thereof for the reception of mercury, a plurality of rollers journaled crosswise of the sluice and partially submerged in the mercury, a second series of rollers disposed above the 15 first-named rollers, said second series of rollers being interspaced to permit them to function as separating and conveying rollers and in the same direction.

first-named rollers, said second series of rollers being interspaced to permit them to 20 function as separating and conveying rollers, and means for rotating both sets of rollers.

4. A device of the character described, comprising a sluice box, said sluice having a compartment formed in the bottom thereof for the reception of mercury, a plurality of rollers journaled crosswise of the sluice and partially submerged in the mercury, a second series of rollers disposed above the 25 first-named rollers, said second series of rollers being interspaced to permit them to 30 function as separating and conveying rollers and in the same direction.

JULIO H. RAE.
